BOOKCASE END TABLE

Frank Y. Biletz, Philadelphia, Pa.

Application August 16, 1940, Serial No. 352,851

2 Claims. (Cl. 312—34)

This invention relates to end tables such as are commonly associated with davenport sets and large easy chairs, and is concerned primarily with end tables of the type in which book shelves are incorporated.

Ordinarily end tables are positioned closely adjacent to an arm of the particular piece of furniture with which it is associated so as to be conveniently accessible to one sitting in that piece of furniture. With those now known end tables that include book shelves the factor of convenience and accessibility to one sitting in the chair has not been carried out to a desired degree because of the relation of the end table to the piece of furniture. The usual disposition has been to have the book shelves open outwardly, away from the piece of furniture. Thus one sitting therein must arise and walk around to a position where he can examine the contents of the book shelf and take out a particular volume desired.

The present invention has in view, as its foremost objective, the provision of an end table of the character above noted which is so designed and constructed that one sitting in an article of furniture with which the end table is associated may examine, select and remove any contents of the book shelves without arising from his seated position.

More in detail this invention has, as an object, the provision of an end table of the character above noted which includes a book shelf that is slidable in the end table. This shelf opens inwardly towards the article of furniture with which the end table is associated, and in normal use of the end table the books are not in a position to be removed. However, when the person in the seated position desires a book from the shelf, the shelf construction may be slid forwardly into a position in which its contents are accessible for selection.

Still more in detail this invention has in view, as an object, the provision of an end table of the type above set forth in which a pair of book shelves are slidably mounted in the end table construction, as above set forth, with one shelf mounted above the other.

The invention has in view, as a further object, the provision of an end table of the character above set forth which includes a slideable book shelf, together with means for yieldably maintaining the same in a retracted position. Means are also provided for yieldably maintaining the shelf in an extended position.

Various other more detailed objects and ad-

vantages of the invention will in part become apparent, and in part be hereinafter stated, as the description of the invention proceeds.

The invention, therefore, comprises an end table which consists of a framework or table structure in which is slidably mounted a pair of book shelves. The book shelves are so arranged that they open inwardly towards the article of furniture with which the end table is associated, and means is provided for yieldably holding each of the book shelves either in a retracted or extended position.

For a full and more complete understanding of the invention, reference may be had to the following description and accompanying drawing, wherein

Figure 1 is a view in side elevation of an end table in which book shelves are incorporated in accordance with the precepts of this invention.

Figure 2 is a top plan view of the structure shown in Figure 1.

Figure 3 is a horizontal section taken about on the plane represented by the line 3—3 of Figure 1.

Figure 4 is a view in end elevation of the table, and

Figure 5 is an enlarged detailed view in section showing the fastening means for yieldably maintaining the shelves in position.

Referring now to the drawing, wherein like reference characters denote corresponding parts, the improved end table of this invention is shown as comprising a table top designated 10, and a bottom structure referred to as 11. Extending between the top 10 and bottom 11 is an outer wall structure 12 which is preferably curved to impart the desired appearance effects to the table. Also extending between the top 10 and bottom 11 is an inner flat wall structure 13 which is intended to be disposed immediately adjacent to the particular article of furniture with which the table is associated.

Carried by the outer wall 12 and inner wall 13, intermediate the top 10 and bottom 11, is a central horizontal partition 14. Slidably positioned between the central partition 14 and the top 10 is a top book shelf referred to in its entirety by the reference character B₁. Another book shelf identified as B₂ is similarly positioned between the partition 14 and the bottom 11. The book shelves B₁ and B₂ are of substantially identical construction. Each comprises a bottom 15, curved end walls 16, and a side wall 17.

It will be noted that when the shelves B₁ and B₂ are in a retracted position, that is in align-

ment with the top 10, partition 14 and bottom 11, the curved end walls 16 blend in with the curved outer wall 12 to provide desired appearance effects.

The upper surface of the bottom 11 is provided with a tongue 19, and the upper surface of the partition 14 carries a similar tongue (dotted lines, Fig. 1). The underface of the bottom 15 of each of the shelves B₁ and B₂ carries a guide groove 18 which receives the corresponding tongue 19 in bottom 11 and the upper surface of partition 14. The tongues 19 and grooves 18 in the bottom of shelves B₁ and B₂ cooperate to guide the respective shelf in its sliding movement from retracted to extended position, and vice versa.

The inner wall 13, at a point adjacent one side edge, carries an element of a fastening device, which element is identified at 20 and shown in detail in Figure 5. This element 20 consists of a U-shaped leaf spring which is anchored to the inner face of the wall 13 by an appropriate fastening means such as a screw shown at 21.

One side of the U-shaped spring engages the wall 13, while the outer or free leaf is formed with an opening 22. Adapted to snap into the opening 22 is a boss or projection 23 formed on the other element of the fastening device, which is identified at 24, and which is carried by the bottom 15 of the book shelf.

As shown in Figure 3, each bottom 15 of the book shelf carries a pair of these elements 24 which are spaced apart. When the boss 23 of one element 24 is snapped into the opening 22 of the other element 20, the shelf is in a retracted position. When the boss 23 of the other element is snapped into the opening 22 of the leaf spring, the shelf is in an extended position.

It is evident that with the element 20 of the snap fastening device adjacent one side edge, as illustrated, the end table is particularly adapted for positioning at one end only one side of an article of furniture, as the shelves are intended to be extended forwardly to render their contents conveniently accessible to one sitting in an article of furniture.

If the table is to be positioned at the other side of the article of furniture, the same may be readily adapted for such positioning by merely chang-

ing the position of the element 20 of the fastening device to a corresponding point adjacent the other side edge. For this purpose the wall 13 is shown as provided with an opening at 25 which is adapted to receive the screw 21 that maintains the element 20 of the fastening device in position.

While preferred specific embodiments of the invention are hereinbefore set forth it is to be clearly understood that the invention is not to be limited to the exact constructions illustrated and described, because various modifications of these details may be provided in putting the invention into practice within the purview of the appended claims.

I. claim:

1. An end table comprising a housing structure having a table top at such height as to be nearly level with the top of an arm of a conventional armchair, side walls and a bottom wall arranged to provide a bookshelf guideway extending entirely through said housing structure, a bookshelf proportioned and constructed to retain books in closely juxtaposed relation to others with their titles facing one wall of said housing structure and arranged in said guideway for projection from either end of said housing structure for inspection of said titles from the side of said housing structure adjacent said last mentioned side wall.

2. An end table comprising a housing structure having a table top at such height as to be nearly level with the top of an arm of a conventional armchair and defining a bookshelf guideway extending through said structure from end to end, a bookshelf having end walls and a connecting member received in said guideway for projection through either end of said housing structure in said guideway, said end walls and connecting member being so arranged as to provide an opening for inspection of titles of books from one side of said bookshelf when it is projected from either end of said housing structure, said ends of said bookshelf defining closure panels for the ends of said guideway when said bookshelf is in fully enclosed position within said guideway.
